PRODUCTION OF TUFTED FABRICS

William Felton, Bradford, England

Application November 28, 1955, Serial No. 549,464

Claims priority, application Great Britain
December 17, 1954

15 Claims. (Cl. 112—79.5)

This invention relates to that kind of loom for producing tufted fabrics, such as carpets, by the application of yarn or thread to an already produced fabric, such as canvas. The main object of the invention is to provide a novel process and means for that purpose which result in the secure attachment of the tufts to the fabric without having yarn extending from one tuft to another and therefore without the using of more thread or yarn than is necessary to produce the tufts themselves.

A process of producing a tufted fabric consists in supporting separate tuft lengths, supporting a piece of fabric, forming holes in the said fabric and drawing the ends of the said lengths through separate of the said holes so that each length remains attached to the fabric whilst the ends project from the holes at one side of the fabric.

The process also consists in feeding the supported tuft lengths and the fabrics so that holes are made in successive parts of the fabric, and the tuft lengths are opposed to said successive parts preparatory to having their ends drawn through the holes.

The process furthermore preferably consists in forcing one projecting end towards the other and thereupon holding projecting ends from interfering with the ends of further tuft lengths inserted into the fabric.

The process furthermore consists in drawing both ends of each tuft length simultaneously through different holes in the fabric as distinguished from pushing the said ends therethrough.

Means for performing the said process preferably includes a feed member which holds tuft lengths, means for moving a piece of fabric, pairs of needles, points for piercing the fabric from that side which is distal from the tuft lengths, notches or holes in the needles for simultaneous engagement by the tuft lengths, and means for closing the notches or holes to facilitate withdrawal of the needles from the fabric, the withdrawal of the needles causing the ends of the tuft lengths to be pulled from the near side of the fabric through the fabric to the distal side thereof whilst leaving an intermediate part of each tuft length at the said near side.

The feed member may be adapted to take and hold yarn or thread in continuous length and there may be cutting means to cut the held yarn or thread into tuft lengths.

The said means furthermore preferably include driving means which drive the feed means and fabric synchronously and intermittently in order to produce dwells in the motion thereof during which the said needles pass through the fabric, are engaged with the tuft lengths and are withdrawn from the fabric.

The said means furthermore preferably include a comb-like support for the fabric where the needles pass through it, the needles being adapted to pass through the gaps in the support.

The means also preferably include a stop which is moved to keep the ends of already inserted tuft lengths

2

clear of the place in the fabric where further tuft lengths are to be inserted.

The means preferably also include a device to act on one end of each tuft length after it has been pulled through the fabric and thereby ensure engagement of the said end by a stop.

The means also preferably include an additional support which operates between the needles to support the fabric at right angles to the support provided by a comb-like support and thereby additionally support the fabric against the drag exerted thereon by the pulling of the ends of the tuft lengths through the fabric.

In the more or less diagrammatic drawings—

Figure 1 is a fragmentary side view in section of a part of a machine for tufting.

Figure 2 is a fragmentary plan view illustrating a detail.

Figure 3 is a fragmentary plan view illustrating another detail.

Figures 4 and 5 together represent a fragmentary rear view partly in section.

Referring to the drawings, in the construction shown therein, there is an intermittently rotatable transporting or feeding means for the filament member 1 which is on a shaft 10 and which can also be subjected to a small amount of axial displacement when required. The member has pairs of supports or blades 2 placed circularly around it at predetermined distances apart, the blades of each pair also being placed at uniform predetermined distances apart. Each blade is provided with a series of notches 3 spaced at suitable distances apart along its length and each adapted to have a different continuous length 4 of thread or yarn pressed into it for example by means of one of a series of discs 5 mounted at the requisite distances apart on a shaft 6' which can be rotated by yarn or thread or other means.

The different continuous lengths 4 of thread or yarn, drawn for example from a creel, are forced in a continuous manner into the notches 3 and fed as the said member 1 and discs 5 rotate.

A series of cutter blades 6 is mounted in a holder 7 which is longitudinally slidably mounted on a slide 8 laterally slidably mounted on a stationary bed 9, whereby the holder 7 can be moved axially relative to the member 1 and simultaneously towards or away from the said member thus imparting to each cutter 6 a localised rotary movement which causes the cutters to enter between each successive pair of blades 2 as each pair comes into register therewith and sever the lengths 4 of yarn at the places where they are stretched between the said pair of blades 2. The combined movement of the holder 7 and therefore the blades 6 is obtained from an eccentric 11 which reciprocates a rod 12 guided in a part 13 of the bed 9 and having a roller 14 which engages a slot 15 in a part 16 of the holder 7, and from eccentrics 17 each connected by a part 18 to the slide 8. The eccentric 11 thus produces the relative axial movement and the eccentrics 17 produce the relative advancing and receding movement. Intermittent rotation of the said member 1 causes each pair of blades 2 successively to register with the cutters 6 and the lengths 4 of yarn or thread are therefore cut by successive cuts into shorter lengths each of which is about equal to a tuft length, the said shorter lengths still being held stretched by the blades 2 so that each length extends from the blade of one pair to the adjacent blade of an adjacent pair.

Near the rotary member 1 there is a support 19 in which a row of thread gripping means or pairs of needles 20 are mounted radially to the rotary member 1. A comb-like rest 21 is arranged between the support and the rotary member with each gap 22 of the rest in register

with one pair of the needles and allowing the said pair simultaneously to be pushed and pulled through it.

The support 19 is first control means or mechanism comprising a pair of cams 23 which cause the needles simultaneously to be pushed through the gaps in the rest into a registering space between adjacent pairs of the blades 2 and then withdrawn from the support 19 through the gaps 22.

Each needle is provided with a closure member or tubular slide 24 through which the needle extends and which is capable of sliding relatively to the needle and thereby either uncovering or covering the mouth of an oblique slot or notch 25 facing in a direction opposite to that in which the rotary member 1 is axially displaced. Each slide 24 has a point 26 and the slides are all mounted on a carrying frame 27 having parts 28 slidable in stationary members 29 and reciprocated by second control means or cams 30 so as to cause them to allow the mouths of the notches 25 to remain uncovered whilst the needles 20 are projected between the adjacent pair of blades 2 and the rotary member 1 is being displaced axially, and thereupon to cover the said mouths and keep them covered until the needles have been drawn back to the distal side of the support 21. The projection of the needles into the space between adjacent pairs of blades 2 and the axial displacement of the rotary member causes one piece cut from the continuous length of yarn or thread to be brought into the notches of both needles of each pair of needles, whilst the said piece is still held stretched by the adjacent blades of two adjacent pairs of blades 2. In Figure 1, a piece cut by one of the cutters 6 is shown and marked 31. Each pair of needles 20 is in a different plane which is at right angles to the axis of rotation of the member 1 and each pair of needles therefore engages a different cut off piece at two spaced places one behind the other. A let-off mechanism is provided to control a shaft on which a roll of fabric, for example canvas is mounted and there are guide and tension members over which the fabric passes before it passes over the support 21 at that side of the support which is nearest the rotary member 1. Some of the fabric is shown in Figure 1 and is marked 32. From the support 21 the fabric passes beneath a stationary guide block 33 to suitable transporting means such as a pair of feed rollers A and B, with the roller A shown as being in driven connection with roller B by a chain E while a chain F passes around a sprocket wheel G secured to roller B and sprocket wheel H on shaft 10 of rotary member 1. A pawl C connected to an arm D rests on a ratchet wheel R fixed to roller B so that when the arm D is oscillated as by a cam 38, the fabric 32 is progressed. Thus, the feed rollers A and B are rotated intermittently to move the fabric 32 at a linear speed which is synchronous with the linear speed at which the cut pieces of the filament or thread are fed by the rotary member to the needles. The interruption in the linear motion of the fabric 32 and the rotary motion of the member 1 is synchronous. That is to say, the first transporting means or rotary member 1 and the second transporting means or feed rollers A and B are thus operatively connected for synchronous intermittent movement so that each pair of thread supports 2 is at a standstill when located opposite the associated fabric portion which is at a standstill. The axial displacement of the member 1 occurs whilst the fabric is stationary and the rotary member is not rotating.

The points 26 of the tubular slides 24 enable the slides 24 to readily penetrate through the fabric 32 on the support 21 when projected through the gaps of the support 21 into position between adjacent pairs of blades 2, this projection taking place whilst the fabric and rotary member are momentarily stationary. The said projection is accompanied by a movement of the needles 20 in the same direction whilst the upper ends of the needles are retracted into the slides 24. The needles thus pass with the slides through the fabric, whereupon the needles and slides then remain projecting from the near side of the

fabric but the slides move to uncover the notches 25 so that the cut piece can be made to enter the notches 25 by axial displacement of the member 1. After the piece has been engaged, the slides 24 move to cover the notches 25 and grip the piece between them and the needles of the pair. The needles and slides are thereupon simultaneously withdrawn back again to the distal side of the support 21. This withdrawl results in each end of each cut piece engaged in a notch 25 and gripped by the corresponding slide 24 against withdrawal from the notches being pulled through a separate hole of the holes made in the fabric by the slides 24, with the result that a portion of each piece remains at that side of the fabric 32 nearest the rotary member 1 whilst the remainder projects from the other side of the fabric to form the projecting part of a tuft. The slides 24 may be operated thereupon to release the ends or the needles be operated so as to forcibly withdraw them from the said ends. Thus a row of tufts is produced in the fabric. To assist the support 21 in supporting the fabric 32 against the pull exerted thereon when the ends are pulled therethrough by the needles 20, there is an auxiliary supporting member 34 having a comb-like upper part to mesh with the comb-like part of the support 21 and adapted to be projected radially into meshing position and withdrawn therefrom by an operating mechanism including cams 35 so as to support the fabric 32 at places which are in register with the gaps 22 of the support and are situated between the needles 20 of each pair.

When a row of tufts has been thus inserted, the fabric 32 and the rotary member 1 are fed a step further so as to bring a fresh part of the fabric into position above the needles 20 and a fresh row of cut off pieces into position for engagement with the needles. To ensure that the already inserted row of tufts shall not interfere with the insertion of the next further row now to be inserted, there is a rocking comb 36 which is suitably driven so that whilst the needles and slides 24 are retracted, the trailing ends of the tufts are pushed by the comb in the direction of travel of the fabric 32 indicated by arrow 37 in Figure 1 but at a greater speed. There is also a bar 37a carried by arm D operated for example by cam 38 so that whilst it is out of the path of the produced row of tufts it moves into a position in front of the trailing end of the last produced row of tufts, is thereupon caused to rise and arrive behind the said trailing ends and finally is caused to travel substantially in the same direction as the fabric at substantially the same speed as the fabric, the oscillating comb 36 assisting the bar 37 in the collection of the ends of the row of tufts in order to ensure that all the said ends shall be out of the way of the needles when they are next moved to project again through the support 21 and fabric 32 into position between one of the said adjacent pair of blades 2 and another adjacent pair of blades 2. The operations repeat themselves to make further rows of tufts.

As all of the necessary motions or nearly all of them can be readily obtained by means of rotary cams, the hereinbefore described machine is capable of operating at speeds which enable an economic output of tufted fabric to be obtained.

Wherever the term "fabric" hereinbefore or herein-after appears it is to be understood that it includes sheet materials, such as sheet rubber, paper and so forth and sheet fabrics such as felt fabric, woven fabric, knitted fabric and so forth. It is also to be understood that the term "yarn or thread" hereinbefore or hereinafter employed includes any kind of filament suitable for tufts.

In a modification, instead of means for axially displacing the rotatable member 1 and therefore also the blades 2, there may be means for axially displacing the pairs of blades 2 only.

In another alternative which may be employed with or without displacement of the rotary member 1 or blades 2, the ends of the needles may be shaped to displace the

stretched shorter lengths laterally against their own resiliency so that they will snap automatically into the notches when the mouths thereof come into register with the said shorter lengths.

I claim:

1. An apparatus for producing tufted fabric comprising, in combination, supporting means for supporting a backing fabric; at least one pair of supports adapted to releasably hold a tuft length at the ends thereof so that the respective tuft length extends straight between said supports, said pair of supports and said supporting means being located relative to each other in such a position that the tuft length extends parallel to and on one side of the supporting means for the backing fabric and opposite to the supporting means; gripping means located opposite said supports; and operating means for reciprocating said gripping means and being located on the side of said fabric supporting means remote from said pair of supports, said operating means moving said gripping means from the other side of said fabric through the same for gripping the tuft length, and moving said gripping means back to the other side of said fabric so that said ends of said tuft length are released by said pair of supports and drawn to the other side of said fabric to form a pile thereon.

2. An apparatus for producing tufted fabric comprising, in combination, supporting means for supporting a backing fabric; at least one pair of supports adapted to releasably hold a tuft length at the ends thereof so that the respective tuft length extends straight between said supports, said pair of supports and said supporting means being located relative to each other in such a position that the tuft length extends parallel to and on one side of the supporting means for the backing fabric and opposite to the supporting means; a pair of pointed gripping means spaced from each other a distance shorter than said supports and being located opposite said supports; and operating means for reciprocating said gripping means and being located on the side of said fabric supporting means remote from said pair of supports, said operating means moving said pair of gripping means from the other side of said fabric through the same for gripping the tuft length, and moving said pair of gripping means back to the other side of said fabric so that said ends of said tuft length are released by said pair of supports and drawn to the other side of said fabric to form a pile thereon.

3. An apparatus as set forth in claim 2 wherein said operating means include cam means.

4. An apparatus as set forth in claim 2 wherein each of said gripping means includes a pointed needle having a transverse notch adjacent the point thereof and a tubular member having a pointed edge and slidably housing the respective needle and being movable along the same for closing and opening said notch, said tubular members being controlled by said operating means to close said notches when said notches engage the tuft length, and to open said notches when said supports have released said tuft length.

5. An apparatus for producing tufted fabric comprising, in combination, supporting means for supporting a backing fabric; at least one pair of supports adapted to releasably hold a tuft length at the ends thereof so that the respective tuft length extends straight between said supports, said pair of supports and said supporting means being located relative to each other in such a position that the tuft length extends parallel to and on one side of the supporting means for the backing fabric and opposite to the supporting means; a pair of pointed gripping means spaced from each other a distance shorter than said supports and being located opposite said supports, each of said gripping means including a needle having a notch and a closure member movable relative to the respective needle for closing and opening the respective notch; operating means located on the side of said fabric supporting means remote from said pair of supports, said oper-

ating means including first and second control means for controlling the movement of said pair of needles and of said pair of closure members, said operating means moving said pair of gripping means from the other side of said fabric through the same, moving said closure members to notch-closing position when a tuft length is engaged in said notches, retracting said gripping means to the other side of said fabric to cause release of the respective tuft length by said supports, and moving said closure members to notch-opening position so that the ends of the tuft lengths form a pile on the other side of the fabric.

6. An apparatus as set forth in claim 5 wherein said closure members are tubular members having pointed edges, each tubular closure member slidably housing the respective needle.

7. An apparatus for producing tufted fabric comprising, in combination, supporting means for supporting a backing fabric; at least one pair of supports adapted to releasably hold a tuft length at the ends thereof so that the respective tuft length extends straight between said supports, said pair of supports and said supporting means being located relative to each other in such a position that the tuft length extends parallel to and on one side of the supporting means for the backing fabric and opposite to the supporting means, said pair of supports being movable in a direction transverse to the plane of said supports; shifting means for shifting said pair of supports in said transverse direction; a pair of pointed

gripping means spaced from each other a distance shorter than the distance between said supports and being located opposite said supports, each of said gripping means including a needle having a notch and a closure member movable relative to the respective needle for closing and

opening the respective notch; operating means located on the side of said fabric supporting means remote from said pair of supports, said operating means including first and second control means for controlling the movement of said pair of needles and of said pair of closure members, said operating means moving said pair of gripping means from the other side of said fabric through the same, moving said closure members to notch-closing position when a tuft length is engaged in said notches, retracting said gripping means to the other side of said fabric to cause release of the respective tuft length by said supports, and moving said closure members to notch-opening position so that the ends of the tuft lengths form a pile on the other side of the fabric; and actuating means for actuating said first and second control means and said shifting

means in a timed sequence so the pair of supports is shifted for inserting a tuft length into said notches when said gripping members are in notch-opening position.

8. An apparatus as set forth in claim 7 wherein said first and second control means include cam means.

9. An apparatus as set forth in claim 5 and including first intermittently movable transporting means, and a plurality of pairs of supports mounted on said transporting means so that upon movement of said first transporting means each of said pairs of supports is successively placed opposite said gripping means; and second intermittently movable transporting means for intermittently transporting said backing fabric so that successive portions of said backing fabric are successively placed opposite said gripping means, said first and second transporting means being connected to each other for movement synchronously and intermittently so that each pair of supports is at a standstill when located opposite the associated fabric portion which is at a standstill.

10. An apparatus as set forth in claim 9 and including a rocking comb located in the region of said gripping means trailing the same in direction of movement of said second transporting means and adapted to be located on the other side of the fabric and being movable in direction of movement of said second transporting means for pushing the ends of tuft lengths projecting from said other

side of said fabric in direction of travel of the fabric and out of the way of said gripping means.

11. An apparatus as set forth in claim 9 and including a bar reciprocable in direction of movement of said second transporting means leading in direction of movement of the same with respect to said gripping means for moving tuft lengths projecting from said other side of said fabric out of the way of said gripping means.

12. An apparatus as set forth in claim 7 and including first intermittently movable transporting means, and a plurality of pairs of supports mounted on said transporting means so that upon movement of said first transporting means each of said pairs of supports is successively placed opposite said gripping means; and second intermittently movable transporting means for intermittently transporting said backing fabric so that successive portions of said backing fabric are successively placed opposite said gripping means, said first and second transporting means being connected to each other for movement in a timed sequence so that each pair of supports is at a standstill when located opposite the associated fabric portion which is at a standstill.

13. An apparatus as set forth in claim 12 wherein said closure members are tubular members having pointed annular edges, each closure member slidably housing the 25 respective needle.

14. An apparatus as set forth in claim 13 wherein said first and second control means include cams.

15. An apparatus for producing tufted fabric comprising, in combination, supporting means for supporting a 30 backing fabric, means for intermittently moving a backing fabric in one direction so that consecutive fabric por-

tions successively assume a predetermined position; feeding means including a plurality of pairs of supports, each pair of supports being adapted to releasably support a tuft length at the ends thereof so that the respective tuft length extends straight between the respective pair of supports, said feeding means being movable for consecutively moving each pair of supports into a position located opposite and spaced from said supporting means for the fabric so that the respective tuft length extends parallel to the respective fabric portion; a pair of pointed gripping means for engaging said lengths of tuft and being spaced from each other a distance shorter than the distance between the supports of said pairs of supports, said gripping means being movable between a retracted position located on the other side of the fabric to an advanced position; operating means for moving said pair of gripping means from retracted position on the other side of said fabric through each of said portions of said fabric to said advanced position for gripping the respective tuft length, and for moving said pair of gripping means back to the other side of said fabric so that said ends of the respective tuft length are released by said pair of supports and drawn to the other side of said fabric to form a pile thereon.
